(57) CLAIM

We claim the ornamental design for a basketball toothbrush, as shown and described.

DESCRIPTION

FIG. 1 is a front view of the basketball toothbrush, showing our new design;

FIG. 2 is a back view of the basketball toothbrush shown in FIG. 1;

FIG. 3 is a side view of the basketball toothbrush shown in FIG. 1; and,

FIG. 4 is a side view of the other side of the basketball toothbrush shown in FIG. 1.
